CLAIM

(51) **LOC (14) Cl.** **14-04**

I claim the ornamental design for a display screen or portion thereof with an animated graphical user interface, as shown and described.

(52) **U.S. Cl.**

USPC **D14/485**

DESCRIPTION

(58) **Field of Classification Search**

FIG. 1 is a front view of a first image in a sequence for a display screen or portion thereof with an animated graphical user interface showing the new design;

USPC D14/485-495

FIG. 2 is a front view of a second image thereof; and,

CPC H04W 4/14; H04W 4/21; H04M 1/724;

FIG. 3 is a front view of a third image thereof.

G06Q 20/326; G06Q 20/322; G06Q 50/01; G06Q 20/384; G06F 3/048; G06F 3/0481; G06F 3/04812; G06F 3/04815; G06F 3/04817; G06F 3/0482; G06F 3/0483; G06F 3/0484; G06F 3/04842; G06F 3/04845; G06F 3/04847; G06F 3/0485; G06F 3/04855; G06F 3/0486; G06F 3/0487; G06F 3/0488; G06F 3/04883; G06F 3/04886; G06F 40/103; G06F 40/106

The outermost broken line rectangle illustrates a display screen or portion thereof and forms no part of the claimed design. The remaining broken lines illustrate portions of the animated graphical user interface that form no part of the claimed design.

See application file for complete search history.

The appearance of the transitional image sequentially transitions between the images shown in FIGS. 1-3. The process or period in which one image transitions to another forms no part of the claimed design.
